Des. 1192

Abel Gray, of Wappingers Falls, N. Y.
Letters Patent No. 1192. Dated Jan'y 24, 1860.

The schedule referred to in these Letters Patent and making part of the same.

To all whom it may concern:

Be it known that I, Abel Gray, of Wappingers Falls in the County of Dutchess, and State of New York, have produced a new and ornamental Design, for Back Combs; and I do hereby declare that the following is a full, clear & exact description of the same, reference being had to the accompanying drawing, making a part of this Specification, in which

Figure 1, represents a front elevation of this invention.

Figure 2, is a transverse vertical section of ditto.

Similar letters of reference, in both views, refer to corresponding parts.

This design consists in combining the frame of a back comb with a series of wave-like projections arranged on the top of the frame alternating with standards of gradually decreasing size from the center towards the ends together with a string of balls of gradually decreasing diameter, from the middle towards both ends, fastened to said standards with the two smallest balls beyond the frame A, as will be hereinafter more fully explained, so as to present an even and handsome curve from end to end.

The frame A of the comb is furnished with teeth B, in the usual manner; that tooth which is in the center of the whole being the longest, while the length of the remaining teeth gradually decreases towards the ends as clearly shown in Figure 1.

The upper edge of the frame A, presents a curved line, provided with two wave-like projections, a, alternately with standards b, the length of which decreases from the middle to the ends, the length of those standards which are at equal distances from the middle of the frame, A, is equal to one another, and they project beyond the edge of the frame to such distances that a line drawn through their tops forms a different curve from the top edge of the frame. The distance of the two middle standards is greater than that of the others and the distance between the two standards gradually decreases towards the ends.

C, is a string of balls containing two more balls than the number of spaces between the standards, b. The string has the largest ball, c, in the middle to fit into the space between the middle or longest one of the standards, b, and balls d, d, e, e, f, and g, of smaller diameters, which decrease gradually towards the last or outer pair of balls, g, g, fill up the spaces between the other standards, as the same succeed one another from the middle towards the ends of the frame A. The last or smallest pair of balls, g, g, is placed outside the last pair of standards, b, as clearly shown in Figure 1, and the several balls are retained by the string of wire passing through them and the standard.

These balls present a handsome gear curve, and by carrying the last pair of balls beyond the standards, or beyond the frame the effect of that portion of the comb which is visible above the hair, is considerably enhanced.

What I claim as new and desire to secure by Letters Patent, is forming the frame A, of the back comb, with a string of balls C, as described, in combination with the standards b, and wave-like projections, a, so as to form a new and ornamental design in the manner herein specified.
